UNITED STATES PATENT OFFICE

CARL C. SHIPPEE, OF FAIR HAVEN, NEW JERSEY

BURNER DEVICE FOR DOMESTIC FURNACES

Application filed February 23, 1929. Serial No. 341,927.

This invention relates to burner devices for domestic furnaces and especially to domestic furnaces which are equipped for oil heating with motor driven oil burners.

5 The invention has for its object generally the provision of a device of the character described, which is efficient, economical and readily installed in conjunction with oil heating devices.

10 A more specific object of the invention is to provide an arrangement of cooperating burners designed to carry particular portions of the heating and at the same time to introduce a high factor of safety in operation 15 of the heating device.

Other objects of the invention will be in part obvious and will in part appear herein-after.

The invention accordingly comprises the 20 features of construction, combination of elements, and arrangement of parts, which will be exemplified in the construction hereinafter set forth and the scope of the application of which will be indicated in the claims.

25 For a fuller understanding of the nature and objects of the invention reference should be had to the following detailed description taken in connection with the accompanying drawings, in which:

30 Fig. 1 is a vertical transverse section of a boiler furnace of the domestic variety constructed in accordance with the invention;

Fig. 2 is a fragmentary horizontal section taken on the line 2—2 of Fig. 1; and

35 Fig. 3 is a sectional view showing details of one of the burner devices employed in accordance with the invention.

Referring now to the drawings and particularly to Fig. 1, 10 denotes a rigid base on 40 which a boiler furnace 11 is supported in the usual manner; the base 10 resting on the floor or other support of the room or building where the furnace is installed. The base 10 is constructed ordinarily to provide an ash

45 pit such as is employed in conjunction with coal-burning furnaces. The base is accordingly shown as having formed about its upper inside edge a plurality of ledges 12 and 13 between which are openings 14 adapted to

50 receive the trunnions of grate bars. Above

the usual location for the grate bars in the boiler furnace is a space 15 which comprises the combustion chamber for the boiler furnace.

The boiler furnace of the present invention 55 is oil heated, consequently no grate bars are shown, and in the ash pit is placed an oil burning device 16 which is preferably operated by an electric motor 17 and is supplied with suitable hydrocarbon fuel from a suitable adjacently located reservoir (not shown in the interest of clearness).

By the present invention, the heating effect of the burner 16 is supplemented by means of gas burners here shown generally at 18. 65 These gas burners are disposed adjacent the oil burner preferably along each side of the ash pit and arranged to project their flames inwardly to cooperate with that of the oil burner. These gas burners are arranged to 70 supply a desired predetermined portion of the heating load of the furnace which, when ascertained, is fixed and the entire regulation of the heating effect is accomplished by regulating the oil burner.

To this end, the gas burners are conveniently disposed as shown in Fig. 1 where the burner nozzles 18 are inserted in the openings for the grate bar trunnions. Details of this arrangement are more readily seen in Fig. 3 where the burner tube 18 is disposed to fit substantially between the ledges 12 and 13 and arranged opposite to an opening 14 in the base 10. To supply such burner nozzle with gas, a jet tube 20 is arranged to extend through the opening 14 into the base of the burner nozzle 18 where it discharges gas at a relatively high velocity so as to pass into the nozzle and thence to the combustion chamber 15. The jet tube 20 is arranged to be 90 supplied with gas from a manifold 21 disposed outside of the base 10 horizontally adjacent the openings 14, so that each burner tube may be supplied with gas from a substantially constant head.

As shown in Fig. 2, a pair of manifolds 21 are preferably employed, one at each side of the base, these manifolds being supported in turn by branched connections 22 and 23 which lead from a supply main 24 leading 100

from any suitable source of gas supply. This main preferably has a gas control valve as shown at 25 interposed therein.

The gas burners here employed as auxiliary burners cooperating with the oil burner, while generally of the Bunsen type, are preferably of a variety adapted to burn relatively large volumes of gas and to effect quickly the proper admixture of air to form a combustible mixture. To this end, the jet tubes 20 are shown as having relatively large bores leading from the manifolds 21; each jet tube having at its outer end a reducing bushing 26 which causes the rapid issuance of a stream of gas that spreads itself cone-like. The burner tube 18, in order to permit this spread of gas, is enlarged at its outer end as indicated at 27 in order to provide a mixing chamber of greater diameter than its inner end. In this way, an adequate supply of air is mixed with the gas prior to its passage through the burner tube 18 into the combustion chamber where it bursts into flame.

The air supply to the mixing chamber 27 of each gas burner is conveniently regulated by means of a movable valve member secured on the jet tube 20. This is conveniently accomplished by providing a valve disk 28 which has threaded engagement with the outside of the jet tube 20 whereby it is readily adjusted along the jet tube. The valve disk 28 when properly adjusted is arranged to be secured in such adjustable position by any suitable means, for example, by means of the lock nut 29 shown jammed against the valve disk 28 in Fig. 3.

In operation, the burner tubes of the present invention are arranged so that the gas burners take a predetermined fixed portion of the load, while the oil burner 16 carries the remaining or variable portion of the load. For example, the gas burners may be adjusted to supply the heat units required by the heating system to compensate the average radiation, the oil burner in such case being arranged to carry the remainder of the heating load. This is advantageous, since the oil burner is readily susceptible to temperature regulating by regulating the speed of the electric motor 17, consequently a properly regulated heating effect may be obtained at all times from the system equipped with the present invention.

In case the electric power at any time goes off, it is seen that the oil burner alone stops functioning, and since the system is now supplied with heat-units through the burners 18 sufficient to take care of a predetermined amount lost by radiation, the house heated by the means of the present invention does not cool below a desired point during the period that the oil burner is out of commission, which is highly advantageous.

It is seen too that the burner devices of the present invention may be very readily sub-

stituted for coal burning equipment of the ordinary boiler furnace, since when the grate bars are removed, the oil burners may be put in place and the gas applied where the grate bar trunnions were, thereby avoiding the cost of boring holes for their reception through the base and at the same time conserving space.

While the present invention has been described in connection with a furnace originally equipped for burning coal, it is obviously not so limited, since any combustion chamber adapted for oil burning may have cooperating gas burners installed adjacent thereto in accordance with the present invention.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a domestic heating device of the character described having a combustion chamber, the combination with a burner disposed in said chamber arranged to burn a mixture of air and hydrocarbon fuel, of an electric motor to actuate said burner, and a plurality of gas burners disposed adjacently to said first named burner arranged to heat the wall of said chamber and to supply a fixed portion of the heating load.

2. In a domestic heating device of the character described having a combustion chamber, the combination with a burner disposed in said chamber arranged to burn a mixture of air and hydrocarbon fuel, of an electric motor to actuate said burner, a plurality of burner tubes horizontally disposed about said first named burner in the base of said combustion chamber adjacent the wall of said chamber, and a manifold device arranged to supply gas to said burner tubes at a substantially constant head of pressure.

3. In a domestic heating device of the character described having a combustion chamber, the combination with a burner disposed in said chamber arranged to burn a mixture of air and hydrocarbon fuel, of an electric motor to actuate said burner, a plurality of burner tubes horizontally disposed about said first named burner in the base of said combustion chamber adjacent a wall of the same, a jet tube projecting into each of said burner tubes adapted to effect cone-like distribution of the gas in said burner tubes, and a manifold device adapted to supply gas to said tubes at a substantially constant head of pressure.

4. In a domestic heating device of the character described having a combustion chamber, the combination with a burner disposed

in said chamber arranged to burn a mixture of air and hydrocarbon fuel, of an electric motor to actuate said burner, a plurality of burner tubes horizontally disposed about said first named burner in the base of said combustion chamber adjacent a wall thereof, a jet tube projecting into each of said burner tubes adapted to effect cone-like distribution of the gas in said burner tubes, and an air regulating means adjustable along said jet tubes arranged to control the air supply to said burner tubes.

5. In a furnace having a combustion chamber adapted for the burning of coal, the combination with a base having openings for the reception of grate bar trunnions, of burner nozzles disposed in said base respectively opposite said grate bar openings, jet tubes projecting from said last named openings and 10 adapted to supply gas to each of said nozzles, and means for supplying gas to said jet tubes at a substantially constant head of pressure.

6. In a furnace having a combustion chamber adapted for the burning of coal, the combination with a base having openings for the reception of grate bar trunnions, of burner nozzles disposed in said base opposite each of said grate bar openings, jet tubes projecting from each of said openings and adapted 15 to supply gas to each of said nozzles, air-regulating means on each of said jet tubes adapted to regulate the passage of air through said openings, and an oil burning device disposed adjacent to said gas burning means at the base of said combustion chamber.

In testimony whereof I affix my signature.
CARL C. SHIPPEE.
